US0D1098957S

(12) **United States Design Patent** (10) Patent No.: **US D1,098,957 S**
(45) Date of Patent: ** Oct. 21, 2025

(54) **SLIDER FOR SLIDE FASTENER**

(71) Applicant: **YKK Corporation**, Tokyo (JP)

(72) Inventor: **Kohei Kawarada**, Toyama (JP)

(73) Assignee: **YKK Corporation**, Tokyo (JP)

(**) Term: **15 Years**

(21) Appl. No.: **29/927,278**

(22) Filed: **Feb. 2, 2024**

(30) **Foreign Application Priority Data**

Oct. 8, 2023 (CN) 202330647333.3

(51) **LOC (15) Cl.** **11-05**

(52) **U.S. Cl.**

USPC **D11/221**

FOREIGN PATENT DOCUMENTS

WO D237562 * 6/2024

Primary Examiner — W. A. Teddy Falloway

(74) Attorney, Agent, or Firm — Kilpatrick Townsend & Stockton LLP

(57) **CLAIM**

The ornamental design for a slider for slide fastener as shown and described.

DESCRIPTION

FIG. 1 is a perspective view of a slider for slide fastener showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings are for the purpose of illustrating portions of the slider for slide fastener that form no part of the claimed design.

The dash-dot lines shown in the drawings define the bounds of the claimed design and form no part thereof.

1 Claim, 7 Drawing Sheets
